UNITED STATES PATENT OFFICE.

ROBERT SLATER, OF PATERSON, NEW JERSEY.

COVERING FOR RAILROAD TIES.

Application filed May 5, 1922. Serial No. 558,805.

To all whom it may concern:

Be it known that I, ROBERT SLATER, a citizen of the United States, residing at Paterson, in the county of Passaic and State 5 of New Jersey, have invented a new and useful Covering for Railroad Ties, of which the following is a specification.

This invention aims to provide novel means for covering and protecting a rail- 10 road tie, adequate means being supplied for holding the rail on the tie.

It is within the province of the disclosure to improve generally and to enhance the utility of devices of that type to which the 15 invention appertains.

With the above and other objects in view, which will appear as the description proceeds, the invention resides in the combination and arrangement of parts and in the de- 20 tails of construction hereinafter described and claimed, it being understood that, within the scope of what is claimed, changes in the precise embodiment of the invention shown can be made without departing from 25 the spirit of the invention.

In the accompanying drawings:—

Figure 1 shows in top plan, a device constructed in accordance with the invention, parts being broken away; Figure 2 is a plan 30 of the blank out of which the device is formed; Figure 3 is a section on the line 3—3 of Figure 1; Figure 4 is a longitudinal section showing a modification.

In carrying out the invention, there is pro- 35 vided a blank 1, made of metal, the blank comprising a rectangular body 2 having openings 3, the body having side wings 4 and end wings 5. The wings 4 and 5 are bent downwardly, and, thus, there results 40 a box-like covering, adapted to be placed about a tie 6, and including a top plate 7, sides 8 and ends 9. The tie, thus, is adequately covered and protected.

Any suitable means may be provided for

holding the rail 12 on the tie 6. If de- 45 sired, the flange 11 of the rail 12 may be engaged by clips 10, bolts 14 passing through the tie 6, the top plate 7 and the clips 10, nuts 15 being threaded on the bolts 14, the nuts engaging the clips 10 and being 50 held in place by cotter pins 16.

In Figure 4, parts hereinbefore described have been designated by numerals previously used, with the suffix "a". In this form of the invention, spikes 17 engage the flange 55 11^a of the rail 12^a and pass downwardly through the openings 3^a in the top plate 7^a into the tie 6^a, instead of the bolts 14 which pass through the openings 3 in that form of the invention which is delineated in Figures 60 1 and 3.

What is claimed is:—

A device of the class described comprising a tie, a plate on the tie, a rail on the plate, and a securing device engaging the rail and 65 extended through the plate into the tie, the plate being provided at its corners with rectangular openings which form wings covering the sides and the ends of the tie, the securing device being spaced from all of the 70 wings whereby the wings may be bent downwardly and shaped to the tie after the plate has been fastened to the tie by the securing device, after the rail is in place, and after the securing device has been permanently 75 mounted and completely secured, the vertical edges of the side wings and the vertical edges of the end wings meeting at the vertical corner edges of the tie, thereby to prevent the end wings from overlapping the 80 side wings.

In testimony that I claim the foregoing as my own, I have hereto affixed my signature in the presence of two witnesses.

ROBERT SLATER. [L. S.]

Witnesses:

CORNELIUS E. MEYER, [L. S.]
JOHN DE VOGEL. [L. S.]
